(57) CLAIM

The ornamental design for a mannequin head, as shown and described.

DESCRIPTION

FIG. 1 is a perspective view of a mannequin head showing my new design;

FIG. 2 is a front view thereof;

FIG. 3 is a rear view thereof;

FIG. 4 is a left side view thereof;

FIG. 5 is a top view thereof; and,

FIG. 6 is a perspective view thereof with a wig.

A bottom view is omitted since the bottom view is invisible in normal use.

The broken line showing of the wig is for the purpose of illustrating the environmental structure and forms no part of the claimed design.
